US00D925907S

(12) United States Design Patent (10) Patent No.: US D925,907 S
Baires et al. (45) Date of Patent: * Jul. 27, 2021

(54) BACKPACK

(71) Applicant: YETI Coolers, LLC, Austin, TX (US)

(72) Inventors: Alex Baires, Austin, TX (US); Derek G. Sullivan, Austin, TX (US); Erik Steven Larson, Austin, TX (US); Vivian Lai, Austin, TX (US); John Loudenslager, Austin, TX (US)

(73) Assignee: YETI Coolers, LLC, Austin, TX (US)

() Term: 15 Years

(21) Appl. No.: 29/646,105

(22) Filed: May 1, 2018

(51) LOC (13) Cl. 03-01

(52) U.S. Cl.

USPC D3/217

(58) Field of Classification Search

USPC ..... D3/215-217, 273, 289, 290, 318, 321, D3/322, 323, 243, 244, 246, 232; 383/72 CPC A45F 4/02; A45F 4/08; A45F 2200/05; A45F 2200/0525; A45F 3/04; A45F 3/042; A45F 3/047; A45F 3/08; A45F 3/10; A45F 3/14; A45C 13/08; A45C 13/083; A45C 13/1046; A45C 2003/007; A45C 3/10

(57) CLAIM

The ornamental design for a backpack, as shown and described.

DESCRIPTION

FIG. 1 is a top, front, right perspective view of a backpack showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, right perspective view of a backpack showing our new design in an open configuration; and,

FIG. 9 is a top, front, right perspective view of a backpack showing our new design in an open configuration.

The broken lines within the shaded areas depict unclaimed stitching. The remaining broken lines depict portions of the backpack that form no part of the claimed design.

1 Claim, 9 Drawing Sheets
